(54) **SAW-SETTING**

(76) Inventor: **Rufus Grandy**

The Schedule referred to in these ~~Letters~~ Patent
and making part of the same containing a description in the
words of the said Rufus Grandy himself of his improvement
in the saw ~~set~~, for setting the teeth of saws.

Bar, made of iron, or of any other suitable material,
a square or other convenient shaped straight bar, having one
of its extremities drawn or shaped to a tapering point, for
the purpose of receiving a handle. Let such handle be fixed
permanently upon it. Let the length of such part of the
said square, or other shaped bar, as appears or shows
itself, outside of the handle aforesaid be equal to five
or six inches more or less, as may be found most conven-
ient. The thickness of the bar aforesaid may be from
one fourth of an inch or less to half an inch, or more,
according to circumstances, a large and stout bar re-
quiring a thickness of material, greater than what will be
sufficient for a thin one.

Imagine, now, that this square, or other
shaped straight bar, as aforesaid, is laid on the table
before you, that the handle of the same points directly
towards you, and that the bar itself, of course, points
directly from you. At about two and a half inches
from the remotest extremity of the bar, but more or less
as convenience requires, let the bar aforesaid be bent
towards your left hand, for instance, or towards your
right, if you prefer it, in manner such as that the
bent of the bar to bend towards your left (or to the
right as the case may be) shall make a right-angled
angle with the former direction of the same part of the
said bar, equal to twenty-five degrees of a circle, more
or less, as may be found to be most convenient to the
purpose to which the said saw ~~set~~ is to be applied.

The bar, bent now in an angular figure, being supposed to be still on the table in the situation; at about half an inch from its farthest extremity, more or less, as may be judged proper, let a screw, with a flat, or other convenient shaped head, be carried through the bent part of the said bar, in a direction parallel with the said table, and at right angles with that part of the bar which it penetrates. When the bar has been bent, and I have supposed, towards our left, the head of the screw is at our left; when the bar has been bent towards our right, the head of the screw is at our right also. Let this screw, from the use it performs, be called the finger-screw. Let also, that part of the bar aforesaid, which is between the handle, and the angle formed by bending, be called, for the sake of distinction, the straight part, and let the other part of the same bar called, for the like reason, the bent part. Moreover, at the said hand carriage or birth of the straight and the bent parts, be called the straight upright surface and bent upright surface of those parts respectively.

Provide now a short bar of iron, or other suitable material of about an inch, square or less, as the case may be, in length and of the same shape, square for instance, as the straight bar just herein mentioned, having one of its longer edges of the same width as the straight upright surface aforesaid. Let one extremity of this short bar, be bevelled off to an angle, much like that made by the two sides of the tooth of a saw, in manner such that the line constituting the edge at angle so made, shall be parallel with the tooth aforesaid, or what is the same thing, perpendicular to the straight upright surface. The proper place for this short bar, when all is put together for use, is a position in which it is parallel with the said straight part, so called, and parallel

to such part of it, as to cause the line or edge made by bending the extremity aforesaid, of the said short bar, to a point towards the angle before mentioned as being made by the straight part and bent part of the original straight bar.

Between the aforesaid straight upright surface, and the corresponding surface of the short bar aforesaid, there is to be interposed, a plate of an uniform thickness, equal to the thickness of the bar, whose teeth it is intended to set and of a rectangular form. The use of this plate is two fold; 1° to make a space or chamber between the straight upright surfaces, and the aforesaid short bar, large or wide enough to receive the saw teeth, near the angle of the straight with the bent part aforesaid; 2° by being confined to a certain position, by means yet to be described, to permit the teeth aforesaid, to be immersed by the chamber, space or chamber aforesaid, to a certain, determinate depth, and no more. Thus it is, that it will accomplish, when by any suitable means this intervening, plate, as I will name it, is made to remain fixed, and stationary, during its time of use, to the straight part of the original bar.

Last of all, suppose what is called a sliding collar made of any suitable material. Let its linear dimensions, that is a transversal section of it were made, in manner such as to exhibit a section of its cavity, the exterior of the section would have the figure of a parallelogram; the shape of a section of the cavity would also be that of a parallelogram whose similar sides are parallel, with those of the former parallelogram. The internal dimensions of this sliding collar would be such as conveniently to allow it to slide over and upon the straight part the intervening plate, and the short bar aforesaid. Let

this collar than, be so slid over the parts just mentioned, while the machine we are describing is lying on the table before us. The saw set is now in a condition fit for use, with the exception of a solitary screw. Enter then, this screw through the right hand end of the collar, as it lies before us, and use this screw which we may call the constricting screw, in such a manner as to press, when they are in their proper positions, the short bar, and the intervening plates, upon the aforesaid straight part of the bar first herein mentioned. The gauge screw being now secured or screwed into the bar as far as may be desirable, in order to bind the tools into the required angle with the face of the saw; the tool-set is ready for use.
